ANTENNA SYSTEM

Raymond M. Wilmotte, New York, N. Y., assignor
to Padevco, Inc., Washington, D. C., a corpora-
tion of Delaware

Application December 12, 1946, Serial No. 715,853

15 Claims. (Cl. 250—33.53)

1

This invention relates to an antenna system for radio broadcasting stations transmitting programs on two different frequencies.

Many broadcasting stations are now transmitting amplitude modulation programs using medium frequencies in the 550 to 1600 kc. band and frequency modulation or television programs on very high frequencies in the 50 or 100 megacycle bands, or higher. Generally the amplitude modulation frequencies are impressed on an array of vertical linear radiators. These radiators are usually, but not always, insulated steel towers. Generally the very high frequency antenna for FM or television must be placed at a height greater than that of the steel towers in order to have adequate coverage. The provision of an additional tower of sufficient height for supporting the very high frequency antenna is expensive and would disturb the radiation pattern of the antenna array if placed on the same plot of ground.

It is an object of this invention to mount the very high frequency antenna at a suitable height without upsetting the radiation pattern of the AM antenna array.

Another object of my invention is to mount a very high frequency antenna at a suitable height and without requiring additional land area.

The invention will be understood from the following description and from the drawing in which: Fig. 1 schematically shows an antenna system for broadcasting programs at two different frequencies, and Fig. 2 shows another embodiment of my invention.

Referring to Fig. 1, there is shown a plurality of vertical radiators 1, 2 and 3 supported on base insulators 4, 5 and 6 respectively. There may be any number of such radiators, and broadcast stations today commonly use between two and five such radiators. The radiators are generally steel towers between one quarter and five eighths wave length in height, although other heights are sometimes used. The steel towers are often self-supporting, but in some cases are provided with guy wires. The antenna array is excited by a network of transmission lines 10 connecting the towers to the broadcast transmitter which will operate on the assigned frequency in the 550 to 1600 kc. band. Networks for adjusting the phase and amplitude of the energy fed to each tower are usually included to obtain the desired radiation pattern. These networks are indicated by the numerals 7, 8 and 9. The towers may be spaced a quarter wave length apart, although other spacings may be dictated by the particular

2

radiation pattern required. The system as so far described is conventional.

On one of the antenna towers, for example 2, a superstructure 11 is erected. The superstructure 11 is supported on the tower 2 by insulators 13. A very high frequency antenna 12 is mounted at the top of structure 11. A suitable transmission line 15 connects the antenna 12 to a very high frequency transmitter (not shown). The transmission line 15 may be a coaxial transmission line or may consist of conductors inside of a conduit, as shown in the application of L. W. Stinson, 525,079, filed March 4, 1944, now Patent #2,441,086 issued May 4, 1948.

15 The structure 11 has a height sufficient to raise the very high frequency antenna to an efficient height. The structure 11, if metallic, would normally have currents induced therein by the radiator 2, as well as by the radiators 1 and 3. These 20 currents in the structure 11 would alter the radiation pattern in a way which is very difficult to predict. In order to obviate or reduce this alternation in the radiation pattern, I provide the following means:

25 A transformer 16 is connected across the insulators 13 and part of the medium radio frequency energy fed to the antennas 1, 2 and 3 is also impressed on transformer 16. The voltages impressed on transformer 16 by transmission line 18 are controlled in phase and amplitude by suitable means 17, well-known in the art. The voltages impressed on transformer 16 are adjusted so that the induced currents in the structure 11 are counterbalanced and reduced to a low value, so 35 that the radiation from the structure is negligible compared with that of the rest of the radiator. A coupling 19 at some point along the structure 11 connected to a meter 20 is used to indicate whether the phase and amplitude adjusting means 40 17 is set to a proper value. The meter 20 may be adjacent the tower structure 11, or may be at ground level. It is evident that more than one coupling circuit 19 and meter 20, suitably spaced along the metallic structure 11, may be used.

45 In Fig. 2 is shown another embodiment of my invention. This figure also shows a three-tower array consisting of antennas 21, 22 and 23 mounted on base insulators 24, 25 and 26. The antennas 21, 22 and 23 may be steel towers. The 50 antennas 21, 22 and 23 are connected to a broadcast transmitter through phase and amplitude controllers 27, 28 and 29 by a transmission line 30. Atop the steel tower 22 are insulators 33, on which is mounted steel tower structure 31. 55 An impedance 32 is connected across the insula-

tors 33. The impedance 32 is connected to the medium frequency transmitter by a transmission line 34 and phase and amplitude controller 35.

At or near the top of the metallic structure 31 is mounted a very high frequency antenna 36 for FM or television broadcasting. Antenna 36 is connected to a transmitter by a transmission line 37 of any suitable type, here shown as a two wire cable having a shield 38. The shield 38 may be the common cable braid, a conduit, or it may take other conventional forms. At a quarter wave length of the medium frequency above ground the shield 38 has a connection 39 to the tower 22. The shield 38 may be in contact or close proximity to the tower 22 from the connection 39 to the insulator 33. At a quarter wave length of the medium frequency above the insulator 33, the shield 38 is connected to the structure 31 by the connection 40.

While it is preferred to space the connections 39 and 40 a quarter wave length above ground and the insulator 33, respectively, it will be understood that the spacing could be any odd number of quarter wave lengths.

The shield 38 and the tower 22 form a shorted quarter wave length transmission across insulator 25, by virtue of the connection 39, and consequently present a high impedance across insulator 25. Similarly, the structure 31 and the shield 38 present a high impedance across insulator 33. Thus, the feeding of the very high frequency antenna 36 is accomplished without introducing low impedances between the tower 22 and ground or the tower 22 and the structure 31.

While the structures 11 and 31 may have any suitable length, I prefer to make the length other than a half wave length of the medium frequency, since it is more difficult to reduce the induced current in a half wave length structure than in structures of other lengths.

Methods other than those I have shown of impressing potentials on the structures 11 and 31 may be used, a number of such other methods being disclosed in my Patents 2,283,617, 2,283,618 and 2,283,619.

The high frequency antennas 12 and 36 are shown schematically. In practice, these antennas take various forms. One form of high frequency antenna consists of a plurality of superimposed single turn loops each lying in a horizontal plane. The high frequency antennas 12 and 36 may be supported by any desired structure mounted on or integral with structures 11 and 31.

I claim:

1. A radio antenna array comprising a plurality of vertical radiators, a vertical conductive structure mounted on one of said radiators and insulated therefrom, a very high frequency antenna mounted on said vertical conductive structure, means for energizing said very high frequency antenna, means for applying relatively low frequency voltages to each of said vertical radiators and to said conductive structure, and means for adjusting the relative phases and amplitudes of the voltages applied to said vertical radiators and to said conductive structure so as to obtain a desired radiation pattern, and so as to reduce to substantially zero current flow in said conductive structure at said low frequency.

2. A radio antenna array comprising a plurality of vertical radiators, a vertical conductive structure insulatedly mounted on one of said radiators as an extension thereof, a very high frequency antenna mounted on said conductive structure, means for energizing said very high frequency

antenna, means for impressing relatively low frequency voltages on each of said vertical radiators and on said conductive structure, means for adjusting the phases and amplitudes of said voltages impressed on each of said vertical radiators to obtain a desired radiation pattern, and means for adjusting the phase and amplitude of the voltage impressed on said conductive structure to reduce the relatively low frequency currents induced in said conductive structure by said vertical radiators.

3. A radio antenna system comprising an array of antenna towers each insulated from ground, a tall metallic structure mounted on one of said towers, an insulator between said metallic structure and the tower on which it is mounted, a high frequency antenna mounted atop said metallic structure, means for energizing said high frequency antenna, means for impressing medium frequency voltages on each of said antenna towers to effect current flow therein, means for impressing a medium frequency voltage between said metallic structure and said one of said towers, and means for adjusting the phase and amplitude of said last named voltage so as to reduce the medium frequency currents induced in said tall metallic structure by current flow in said antenna towers, and means for indicating the current flowing in said metallic structure.

4. A radio antenna system comprising an array of antenna towers, each insulated from ground, a tall conductive structure mounted on one of said towers, an insulator between said conductive structure and the tower on which it is mounted, a high frequency antenna mounted atop said conductive structure, means for energizing said high frequency antenna, means for impressing relatively low frequency voltages on each of said antenna towers, means for impressing a relatively low frequency voltage between said conductive structure and said one of said towers, and means for adjusting the phase and amplitude of said last mentioned voltage in such mode as to reduce relatively low frequency currents induced in said conductive structure by said array.

5. A radio antenna system comprising an array of antenna towers, each insulated from ground, means for energizing said array by relatively low frequency voltages, a metallic structure mounted on one of said towers, an insulator between said metallic structure and the tower on which it is mounted, a high frequency antenna mounted atop said tall metallic structure, a transmission line coupled with said high frequency antenna and extending adjacent said tall metallic structure and the tower on which it is mounted, a metallic shield encompassing said transmission line, means for grounding one end of said shield, means connecting said shield to said last mentioned tower at a point substantially a quarter wave length of said relatively low frequency above ground, means for impressing said relatively low frequency voltage on said metallic structure, and means for adjusting the phase and amplitude of said voltage impressed on said metallic structure to reduce the currents induced therein by currents flowing in said array in response to said relatively low frequency voltages.

6. The apparatus described in claim 5, including, means for connecting said shield to said metallic structure at a point substantially a quarter wave length of said relatively low frequency above said insulator.

7. A radio antenna array comprising a plurality of vertical radiators, means for energiz-

ing said vertical radiators to radiate a predetermined space pattern of radio frequency energy, a further antenna, means comprising a conductive tower for supporting said further antenna on one of said vertical radiators, and means for substantially reducing current flow in said conductive tower at the frequency of said energy for reducing distortion of said predetermined space pattern occurring in response to currents induced in said conductive tower by said antenna array.

8. A radio antenna array comprising a plurality of vertical radiators, means for energizing said vertical radiators to radiate a predetermined space pattern of radio frequency energy, a further antenna, means comprising a conductive tower for supporting said further antenna on one of said vertical radiators and means for substantially reducing distortion of said predetermined space pattern in response to currents induced in said conductive tower by said antenna array, said last named means comprising circuit means for applying to said conductive tower voltages of adjustable phase and amplitude.

9. A radio frequency antenna system comprising a plurality of relatively space positioned vertical radiating elements, each of said radiating elements comprising a vertical ground supported metallic frame structure, means comprising a source of radio frequency energy for energizing said vertical radiating elements in predetermined relative phase and amplitude to establish a predetermined radiation pattern of radio frequency energy, means comprising a metallic antenna mast insulatedly supported by at least one of said vertical radiating elements and having a current distribution therein in response to said radiation pattern of radio frequency energy, and means for minimizing said current distribution by introducing an opposing current distribution in said metallic mast, said last named means comprising said source of radio frequency energy and means comprising a phase and amplitude controller for coupling said source of radio frequency energy with said metallic antenna mast.

10. A radio frequency antenna system comprising a plurality of relatively space positioned vertical radiating elements, each of said radiating elements comprising a vertical ground supported metallic frame structure, means comprising a source of radio frequency energy for energizing said vertical radiating elements in predetermined relative phase and amplitude to establish a predetermined radiation pattern of radio frequency energy, means comprising a metallic antenna mast insulatedly supported by at least one of said vertical radiating elements and having a current distribution therein in response to said radiation pattern of radio frequency energy, and means for minimizing said current distribution by introducing an opposing current distribution in said metallic mast, said last named means comprising said source of radio frequency energy, and means comprising a phase and amplitude controller for coupling said source of radio frequency energy with said metallic antenna mast, a metallic linear member extending for substantially the entire length of said metallic mast and of said at least one of said vertical radiating elements and supported thereby, means for electrically connecting said linear member to said at least one of said vertical radiating elements at at least one point adapted to establish a high impedance circuit as seen adjacent ground for said at least one of said vertical radiating ele-

ments and said metallic linear element when considered as a resonant transmission line.

11. A radio antenna array comprising a plurality of vertical radiators each insulated from ground, means for energizing said vertical radiators to radiate a predetermined space pattern of radio frequency energy, a further antenna, means for supporting said further antenna on one of said vertical radiators, comprising a conductive tower electrically isolated from said one of said vertical radiators by insulating means, and means for substantially reducing distortion of said predetermined space pattern in response to currents induced in said conductive tower by said antenna array, comprising circuit means for applying between said conductive tower and said one of said vertical radiators voltages of adjustable phase and amplitude derived from said means for energizing said vertical radiators.

12. A radio antenna array comprising a plurality of vertical radiators each insulated from ground by insulating means, means for energizing said vertical radiators to radiate a predetermined space pattern of radio frequency energy, a further antenna, means for supporting said further antenna on one of said vertical radiators comprising a conductive tower electrically isolated from said one of said vertical radiators by insulating means, and means for substantially reducing distortion of said predetermined space pattern in response to currents induced in said conductive tower by said antenna array comprising circuit means for applying between said conductive tower and said one of said vertical radiators voltages of adjustable phase and amplitude derived from said means for energizing said vertical radiators, means for applying energy to said further antenna comprising a transmission line having a shield supported at least in part by said conductive tower, and means for preventing short circuiting of said insulating means by said shield comprising conductive connections between said shield and said conductive tower and between said shield and said one of said vertical radiators, said conductive connections being located along said shield at points adapted to establish high impedance circuits as seen across said insulating means for the frequency of said radio frequency energy.

13. A radio antenna array comprising a plurality of vertical radiators, a vertical conductive structure insulatedly mounted on one of said radiators as an extension thereof, means for impressing relatively low frequency voltages on each of said vertical radiators and on said conductive structure, means for adjusting the phases and amplitudes of said voltages impressed on each of said vertical radiators to obtain a desired radiation pattern, and means for adjusting the phase and amplitude of the voltage impressed on said conductive structure so as to reduce the currents induced in said conductive structure by said vertical radiators.

14. A radio antenna system comprising an array of antenna towers each insulated from ground, a tall metallic structure mounted on one of said towers, an insulator between said metallic structure and the tower on which it is mounted, means for impressing alternating current voltages on each of said antenna towers to effect current flow therein, means for impressing a further alternating current voltage at the frequency of said first mentioned voltages between said metallic structure and said one of said towers, and means for adjusting the phase and

amplitude of said last mentioned voltage so as to reduce the magnitude of current induced in said tall metallic structure by current flow in said antenna towers.

15. A radio antenna system comprising at least one vertical radiator insulated from ground, means for energizing said vertical radiator to radiate a predetermined space pattern of radio frequency energy, a further antenna, means for supporting said further antenna on one of said vertical radiators comprising a conductive tower electrically isolated from said one of said vertical radiators by insulating means, and means for substantially reducing distortion of said predetermined space pattern in response to currents induced in said conductive tower by said antenna array comprising circuit means for applying between said conductive tower and said one of said vertical radiators voltages of adjustable phase and amplitude derived from said means for energizing said vertical radiators, a ground located radio equipment, means for interconnecting said further antenna and said ground located radio equipment comprising a transmission line having a shield supported at least in part by said conductive tower, and means for preventing short circuiting to said radio frequency energy of said insulating means by said shield comprising con-

ductive connections between said shield and said conductive tower and between said shield and said one of said vertical radiators, said conductive connections being located along said shield at points adapted to establish high impedance as seen across said insulating means for the frequency of said radio frequency energy.
